UNITED STATES PATENT OFFICE.

WILLIAM J. MOELLER, OF WYOMING, OHIO, ASSIGNOR TO THE PHILIP CAREY MANUFACTURING COMPANY, OF LOCKLAND, OHIO, A CORPORATION OF OHIO.

BAG.

1,104,308.

Specification of Letters Patent.

Patented July 21, 1914.

Application filed March 1, 1911. Serial No. 611,605.

To all whom it may concern:

Be it known that I, WILLIAM J. MOELLER, a citizen of the United States, residing at Wyoming, in the county of Hamilton and 5 State of Ohio, have invented certain new and useful Improvements in Bags, of which the following is a specification.

My invention relates to improvements in bags as articles of manufacture. 10 The object of my invention is to save material in the construction of bags, thereby reducing the cost, and to render the bags more convenient for tying and easier to empty into receptacles without spilling than 15 otherwise.

Heretofore in the construction of bags they have been formed rectangular in shape, with a mouth or opening extending entirely across one end. When so constructed, 20 a large amount of the open end of the bag is required to be gathered together in tying, thus materially reducing the capacity of the bag.

My invention enables a bag to be constructed out of much less material, and at the same time having the same capacity, when tied shut as bags of the ordinary construction.

My invention consists in forming the bag 30 at its upper or open end with a cut away portion at one side forming an outwardly extending narrow or contracted neck which may be readily gathered in tying, and which forms a spout through which the contents 35 may be easily discharged without spilling when emptying the bag.

My invention also consists in the bag as herein claimed.

In the accompanying drawing which 40 serves to illustrate the construction and use of my invention: Figure 1 is a diagrammatic view of a strip of material showing how the material may be cut without waste. Fig. 2 is a side view showing the shape of 45 the bag after it is sewed or stitched, and showing by dotted lines at the top the size and shape of a bag of the same capacity when made in the usual way, when said bags are tied shut. Fig. 3 is a perspective view when the bag is filled with material 50 and tied. Fig. 4 is a section on the line 4—4 of Fig. 2.

In the manufacture of bags in accordance 55 with my invention, I preferably take a strip of material 1, and cut it into the parts 2 in

the manner shown in Fig. 1, thus cutting the material for each bag in such manner as to permit of no waste of the goods. Each part 2 is then folded longitudinally on the dotted line 3, and is secured and formed into a bag 60 by stitches or seams 4, as shown in Fig. 2. The bag as thus formed is provided with an outwardly extending contracted neck or mouth 5 and the amount of goods saved in the construction of each bag is represented 65 by the space 6 between the top of the bag illustrated in Fig. 2 and the dotted line 7 at the top thereof. The bag may be filled through the mouth 5 and then tied, as illustrated in Fig. 3, or it may be first tied in 70 that manner and then filled through an opening provided with a valve at the other end of the bag, in the manner that cement bags are now commonly filled.

The bags made in accordance with my invention are preferably constructed of canvas or burlap, but may be made of any flexible material, such as paper, duck or the like. These bags so constructed are especially adapted and intended for use as cement bags, 80 but they will also be valuable as wheat sacks and may be formed of paper to great advantage for flour sacks, and for other purposes.

My invention is capable of some modification without material departure from its 85 scope or spirit.

The importance and value of my invention will be apparent when the nature and vast extent of the bag industry is considered, and the saving and advantages are consequently 90 very great.

In addition to the various other advantages of my invention, when the bag is used for cement and the like and it is desired to close the opening by sewing as is commonly 95 done, after the bag has been filled, a great saving in labor is effected by having a comparatively small opening (such as is obtained by my invention) to sew up.

I claim:

1. As an article of manufacture, a bag cut away to form an outwardly extending contracted neck and opening at the top on one side thereof, and suitable means for closing said opening, substantially as set forth and 105 for the purposes specified.

2. As an article of manufacture, a bag having a longitudinal seam, said bag being cut away at the top adjacent said longitudinal seam to form an outwardly extending 110

contracted neck and opening, at one side of the top of the bag, and suitable means for tying said outwardly extending neck to close said opening, substantially as set forth and for the purposes specified.

3. A bag comprising a main body portion and provided with a tapered outwardly ex-

tended open neck at one side thereof, and means for closing said neck.

WILLIAM J. MOELLER.
